No. 687,450.

Patented Nov. 26, 1901.

R. CONRADER.

PUMP GOVERNOR.

(Application filed Apr. 4, 1901.)

(No Model.)

UNITED STATES PATENT OFFICE.

RUDOLPH CONRADER, OF ERIE, PENNSYLVANIA.

PUMP-GOVERNOR.

SPECIFICATION forming part of Letters Patent No. 687,450, dated November 26, 1901.

Application filed April 4, 1901. Serial No. 54,290. (No model.)

To all whom it may concern:

Be it known that I, RUDOLPH CONRADER, a citizen of the United States, residing at Erie, in the county of Erie and State of Pennsylvania, have invented certain new and useful Improvements in Pump-Governors; and I do hereby declare the following to be a full, clear, and exact description of the invention, such as will enable others skilled in the art to which it appertains to make and use the same.

This invention relates to pump-governors; and it consists in certain improvements in the construction thereof, as will be hereinafter fully described, and pointed out in the claims.

More particularly, the invention relates to a type of governor shown in a previous application filed by me on September 10, 1900, Serial No. 29,490. In the application referred to a governor is shown wherein there is a speed-governor and a pressure-governor combined, in which the strength of the centripetal element is varied by a change in the pressure on the pressure device. In the construction shown in that application there is a compensating mechanism formed by a spring for controlling the action of the pressure device upon the said centripetal element, so that the governor is more sensitive to changes of receiver-pressure.

In the present application I have substituted for the spring compensating device a weighted compensating device having a lever mechanism presenting varying arms as the device moves. I have also provided a peculiar construction of pressure device and also a peculiar construction of the automatic stop mechanism, as well as details of construction, which will fully appear in the claims.

The invention is illustrated in the accompanying drawings, as follows:

Figure 1 shows a section on the line 1 1 in Fig. 2. Fig. 2 shows a section on the line 2 2 in Fig. 1. Fig. 3 shows a detail of the automatic stop mechanism. Fig. 4 shows a detail of the compensating-lever mechanism. Fig. 5 shows a section of a fragment of the device on the line 5 5 in Figs. 1 and 2.

A marks the valve-chamber, and B the valve, which is arranged to operate in the diaphragm a of the valve-chamber as usual. Secured to the valve-chamber A is the frame C by means of a base-plate C'. The frame C has the arm c, in which is journaled the drive-

shaft d, the upright extension c', in which is 55 journaled the rotating carrier of the speed-governor, and the arm c², with which the pressure device is connected. Extending upwardly from the valve is the valve-stem b, and a gland a' is provided, as usual, for this 60 stem. The stem is secured to a lever-block b², and an extension b' extends from this block to the speed-governor. The governor is driven through a pulley D, which operates the drive-shaft d and actuates the gear d'. This gear d' drives the gear e. The gear e is fixed with the rotating carrier E. Centrifugal weights F F are pivoted on the carrier at the points f f below their centers of gravity. A cross-head b³ is secured to the top of the 70 stem b', and links b⁴ secure the cross-head with the weights.

Pivoted on the pin c³ in the arm c² is the lever G. This lever is provided with the rounded end g, which operates in the lever-block b², so as to move with said block, and consequently with the valve B. This lever is provided with the rounded end g', and resting upon it is the nut h', which is secured to the rod h. A nut h³ is secured to the rod h 80 below the end of the lever g. The rod h extends through a nut H', and tensioned between this nut and an elongated nut h⁴ is a spring H, the spring H being of considerably greater strength than the spring H'. The 85 nut H' is secured in a frame I, which extends around and by the springs H' and H and the lever G, and is provided at its end with a pin I', which rests upon the piston of the pressure device. Extending from the frame is a lug 90 i, and secured in this lug is a guide-bolt i'. The guide-bolt extends through a lug c⁴ on the arm c².

A fork-lever J is pivoted on the pin c³ and passes outside of the frame I. A lever J' is 95 secured in this fork. Extending downwardly from the fork J are the arms J². The links J³ connect the lower ends of the arms J² with the upper end of the frame I. Secured to the outer end of the lever J' is an upright 100 post J⁴, and adjustably secured on this post by means of set-screws or otherwise is a weight J⁵.

A cylinder L is passed through a projection C², extending from the plate C, and is secured 105 in said projection by means of a shoulder l below said projection and a flange-nut l', screwed onto said cylinder above said projec-

tion. A piston L' is arranged in the cylinder and operates against the stem. Below the cylinder L is an oil-chamber M . Extending upwardly into this chamber is a cylindrical cup m . This cup is provided at its lower end with a small flange m' , which rests against the bottom of the chamber M . The cup is secured in place by means of a flange-nut m^2 , embracing said cup and being screwed onto the end of the chamber. Operating in this cup is a plunger m^3 , which forms an extension to the piston L' . In assembling the parts the plunger is placed in the cup. This centers it, and the nut m^2 is then forced to place. Extending through the bottom of the wall of the cup is a minute opening m^4 . The cup is slightly smaller at the bottom than the chamber M , forming the passage m^5 between the cup and the chamber. The plunger m^3 is provided with a passage m^6 , and a minute opening m^7 communicates with this passage. This passage is preferably filled with waste or asbestos fibers, and extending from this passage to the surface of the piston L' is a minute passage m^8 . A connection m^9 is made with the pump-receiver. The chamber M preferably carries sufficient oil to fill the cup m .

The operation of the parts of the governor described is as follows: The centripetal governor operates in its usual manner. The piston L' being in its lowermost position, the spring H^2 is practically out of operation, so that the centripetal element of the governor is formed by the spring H . This gives to the governor the widest valve-opening with the least speed. When the pressure exceeds a desired minimum, it operates upon the piston L' . An exerting pressure upon the oil in the chamber M forces oil through the minute opening m^4 , and thus operates against the plunger m^3 . The effect of this is to raise the frame I and reduce the tension of the spring H , thus reducing the centripetal element of the governor and giving to the valve a smaller opening with the same speed, and consequently, or, in other words, speeding the governor down, so as to give to the pump a slower speed. It will be noted that the piston L' is only subjected to the direct air-pressure on a part of its surface, so that it will not operate except through the addition of pressure through the plunger m^3 and that the pressure on the plunger can only follow the action of the piston as the oil passes through the minute opening m^4 . This prevents any slamming and insures a smooth even movement. When the parts are returned through a decrease in the receiver-pressure, the same dash-pot effect is obtained. In each one of these actions a small quantity of oil is forced into the passage m^6 and out through the opening m^8 . This escape of oil constantly lubricates the piston L' and forms an oil seal between the piston and the cylinder.

In the manner described in the prior application as the piston moves upwardly the ten-

sion of the spring H decreases, and as this spring exerts pressure in the direction of the pressure device a considerable change in counter-pressure or receiver-pressure is necessary to effect a continued movement of the frame I . In order to neutralize to some extent this change in tension of the centripetal spring, I provide a weighted lever J with the downwardly-extending arms J^2 . It will be noted that as the frame I moves upwardly the arm J^2 is swung outwardly from the pivot c^3 , thus forming a greater length of arm between the fulcrum and the power and at the same time decreasing the length of the arm between the power and the weight, so that the effect of the weight decreases as the tension on the centripetal spring decreases. In this manner a considerable movement may be effected in the frame I with a very small difference in the receiver-pressure, so that the pump may be controlled so as to give just the necessary speed to furnish a supply equal to that drawn from the receiver. The effect of the changing arm may also be accomplished by extending the weight J^4 a distance above the pivot c^3 . It will readily be seen that as the weight J^4 is extended above this pivot it swings inwardly with an upward movement of the lever, so as to shorten the arm J' . Where the weight is adjusted to the lower end of the post this change is very small. By this means and the arm J^2 a very nice adjustment may be accomplished, so that the decrease in tension on the spring H^2 may be as nearly compensated for as desirable, and in this way the governor may be made to effect a speed in the engine which will have a sufficient variation to maintain the receiver-pressure within very narrow limits.

Pivoted on the pin C^3 is a stop-lever O . It extends preferably to the opposite side of the machine from the lever J . It is provided with a roll o at its outer end, and extended from this lever is a weight O' . A rider-pulley N is arranged to operate upon the belt, as ordinarily with stop devices. This is carried by an arm n . The arm n is secured in the ring N' . The ring N' is clamped on a flange-collar N^2 by means of a clamping-bolt n^2 . The flange-collar N^2 is provided with a segmental flange n' . In setting the governor the roller o is placed on the flange n' and the clamping-spring N' loosened. The rider-pulley N is placed upon a belt and the clamp-ring N' set up so as to hold it in this position. If the belt should break, the rider-pulley falls and carries the flange n' from under the roller o and allows the lever O to drop. The inner end of the lever has upwardly-projecting lugs o' , and a pin o^2 extends between these lugs on the lever G . It will readily be seen that as soon as the lever O drops the lever G is carried downwardly by the pin o^2 , and this closes the valve B .

What I claim as new is—

1. In a pump-governor, the combination with the governor-valve; of a pressure device

actuated by the pumped fluid; a lever mechanism connected with said pressure device; a counterweight connected with said lever mechanism in opposition to the pressure device, said pressure device and counterweight being arranged to operate against each other through said lever mechanism, on a relatively varying arm; and a connecting mechanism between said pressure device and governor-valve, said mechanism being arranged to influence the action of the governor-valve with a movement of the pressure device.

2. In a pump-governor, the combination of a speed-governor comprising a centrifugal and a centripetal element; a governor-valve; a pressure device actuated by the pumped fluid; a lever mechanism connected with said pressure device; a counterweight on said lever mechanism, said lever mechanism being arranged to operate upon one of the elements of the governor and to present a varying arm to the counterweight and pressure device.

3. In a pump-governor, the combination of a speed-governor comprising a centrifugal and a centripetal element; a governor-valve; a pressure device actuated by the pumped fluid; a lever mechanism connected with said pressure device; a counterweight on said lever mechanism, said lever mechanism being arranged to operate upon one of the elements of the governor and to present a varying arm to the counterweight and pressure device to compensate for the variation in counter-pressure on the pressure device through the action of the speed-governor element.

4. In a pump-governor, the combination of a speed-governor comprising a centrifugal and a centripetal element; a governor-valve; a pressure device actuated by the pumped fluid; a lever mechanism connected with said pressure device; a counterweight on said lever mechanism, said lever mechanism being arranged to operate upon the centripetal element of the governor and to present a varying arm to the counterweight and pressure device.

5. In a pump-governor, the combination with the governor-valve; the centripetal and centrifugal elements; of a pressure device actuated by the pumped fluid; a lever mechanism connected with said pressure device; a counterweight on said mechanism and arranged in opposition to the pressure device, said pressure device and counterweight being arranged to operate against each other through said lever mechanism on a relatively varying arm; and a connecting mechanism between said pressure device and one of the elements of the governor for varying the strength of one of the elements of the governor relatively to the other of said elements within the limit of the power exerted by said other element.

6. In a pump-governor, the combination with the governor-valve and the centrifugal and centripetal elements; of a pressure device actuated by the pumped fluid; a lever mechanism connected with said pressure de-

vice; a counterweight on said mechanism and arranged in opposition to the pressure device, said pressure device and counterweight being arranged to operate against each other through said lever mechanism on a relatively varying arm; and a connecting mechanism between said pressure device and the centripetal element of the governor, said connecting mechanism being arranged to vary the strength of the centripetal element with a movement of the pressure device within the limits of the power exerted by the centrifugal element.

7. In a pump-governor, the combination with the governor-valve; a pressure device actuated by the pumped fluid; a pivoted lever connected with said pressure device; a weight on said lever; an arm extending from said lever out of the line between the pivot and the weight; and a connection between said arm and said valve, said arm being arranged to vary the lever-arm with a movement of the pressure device.

8. In a pump-governor, the combination with the governor-valve; of a pressure device actuated by the pumped fluid; a pivoted lever connected with said pressure device; a weight on said lever; means for adjusting said weight in a vertical direction to vary its movement toward and from the pivot with a movement of the lever; and a connection between said lever and said valve, said connecting mechanism being arranged to influence the action of the governor-valve with a movement of the pressure device.

9. In a pump-governor, the combination with the governor-valve; of a pressure device actuated by the pumped fluid; a pivoted lever connected with said pressure device; a weight on said lever; means for adjusting said weight in a vertical direction to vary its movement to and from its pivot with a movement of the lever; an arm extending from said lever out of the line between the pivot and the weight; and a connection between said arm and said valve, said connection being arranged to influence said valve with a movement of the lever.

10. In a pump-governor, the combination of a speed-governor comprising a centrifugal and a centripetal element; a governor-valve; a pressure device actuated by the pumped fluid; a pivoted lever connected with said pressure device; a weight on said lever exerting a counter-pressure on the pressure device; an arm extending from said lever out of the line between the pivot and the weight; a weight between said arm and the pressure device; a connection between the pressure device and the centripetal element of the governor, the said centripetal element being arranged to exert a counter-pressure upon the pressure device, the said variation in the lever-arm tending to compensate for a variation in counter-pressure on the pressure device due to the action of the pressure device on the centripetal element of the governor.

11. In a pump-governor, the combination with the centripetal and centrifugal elements; a governor-valve actuated by said elements; the lever, G, arranged to act with the valve 5 and centrifugal element of the governor; the springs, H and H², arranged to operate upon said lever; the frame, I, and pressure device operating upon said frame; the pivoted lever, J; the arm, J², extending downwardly from 10 said lever out of the line between said lever and the weight; the weight, J⁵, on said lever; and a link, J³, connecting the arm, J², with the frame, I.
12. In a pressure device, the combination 15 of a cylinder; an actuating-piston within said cylinder; an oil-chamber; a plunger extending from said piston; a cylindrical cup in which said plunger operates; a minute passage leading from said chamber to said cup 20 for the purpose described.
13. In a pressure device, the combination of a cylinder; an actuating-piston within said cylinder; an oil-chamber; a plunger extending from said piston; a cylindrical cup in 25 which said plunger operates; a passage leading from said chamber to said cup; and a passage leading from said cup through the plunger and piston to the surface of the cylinder.
14. In a pressure device, the combination 30 of a cylinder; an actuating-piston within said cylinder; an oil-chamber; a plunger extending from said piston; a cylindrical cup in which said plunger operates; a minute passage leading from said cup through the plunger 35 and piston to the surface of the cylinder.
15. In a pressure device, the combination of the cylinder, L; the piston, L'; the oil-chamber, M; a cup extending upwardly in the oil-chamber; a plunger extending from the piston 40 into said cup, said plunger and piston being provided with a passage leading from a cup into the surface of the cylinder, the walls of said cup having a passage leading from the oil-chamber into said cup.
- 45 16. In a pump-governor, the combination of a regulating-valve; a pressure device actuated by the pumped fluid; a connecting mechanism between said pressure device and said valve, said pressure device comprising a cylinder and a piston operating in said cylinder; an oil-chamber; means whereby the oil may be subjected to the pumped-fluid pressure and for communicating said pressure to the piston, said means comprising a minute opening for effecting a dash-pot action on the piston.
- 50 17. In a pump-governor, the combination of a centrifugal and a centripetal element; a governor-valve actuated by said elements; a pressure device actuated by the pumped fluid; a connecting mechanism between said pressure device and said valve, said pressure device comprising a cylinder and a piston operating in said cylinder; an oil-chamber; means 55 whereby the oil may be subjected to the pumped-fluid pressure and for communicating
- ing said pressure to the piston, said means comprising a minute opening for effecting a dash-pot action on the piston.
18. In a pump-governor, the combination 70 of a centrifugal and a centripetal element; a governor-valve actuated by said elements; a pressure device arranged to operate upon said centripetal element and to vary the force of said centripetal element within the power of 75 said centrifugal element, said pressure device comprising a cylinder, a piston, an oil-chamber, means for subjecting the oil to the pump-pressure and for subjecting the piston to the pressure from the oil-chamber, the 80 movement of the oil in exerting pressure upon the piston being checked by a minute opening to effect a dash-pot action upon the piston.
19. In a pump-governor, the combination 85 of the governor-valve; a centrifugal and a centripetal element; a pressure device arranged to operate upon said centripetal element to vary the force of said element; a lever mechanism connected with said pressure device; 90 a counter-pressure mechanism connected with said lever mechanism and operating against said pressure device on a relatively-varying arm, said pressure device comprising a cylinder, a piston, an oil-chamber, means for subjecting the oil in the chamber to the pump-pressure and conveying the pressure through the oil to the piston; and means for checking 95 the movement of oil with a movement of the piston to effect a dash-pot action on the piston.
20. In a pump-governor, the combination 100 with the centripetal and centrifugal elements; a governor-valve actuated by said elements; a pressure device; a connecting mechanism 105 between the pressure device and the valve, comprising a lever, G; the lever, O, having the lugs, o'; cross-pin, o²; weight, O', on the lever, O; a rider-pulley; an arm extending from said rider-pulley to a means for normally sustaining the arm, O, said means being arranged to drop the arm, O, upon a movement of the rider-pulley out of its normal path.
21. In a governor, the combination of means 110 for supporting an automatic stop mechanism; a clamping-ring, N', arranged on said means; a rider-pulley, N, carried by said clamping-ring, whereby said rider-pulley may be adjusted to any angle of belt.
22. In a governor, the combination of the rider-pulley, N; the arm, n; clamping-ring, N'; the flange-ring, N², on which the clamping-ring is arranged; the flange, n', on the flange-ring; and the automatic stop-arm, O, 115 arranged on the flange, n'.
